UNITED STATES PATENT OFFICE.

JAMES RAPHAEL ROSSETTER, OF KNOXVILLE, TENNESSEE, ASSIGNOR TO THE WM. J. OLIVER MANUFACTURING COMPANY, OF KNOXVILLE, TENNESSEE, A CORPORATION OF TENNESSEE.

PLOW.

949,688.

Specification of Letters Patent. Patented Feb. 15, 1910.

Application filed May 7, 1909. Serial No. 494,529.

To all whom it may concern:

Be it known that I, JAMES RAPHAEL ROSSETTER, a citizen of the United States, residing at Knoxville, in the county of Knox 5 and State of Tennessee, have invented certain new and useful Improvements in Plows; and I do hereby declare the following to be a full, clear, and exact description of the invention, such as will enable others skilled 10 in the art to which it appertains to make and use the same.

The object of my invention is to improve the construction of a moldboard plow by increasing its strength and more perfectly securing its parts together so as to hold the 15 original shape and relation of the parts necessary for a perfectly operating implement; and also to simplify the construction of a plow having its working parts fitted and 20 detachably fastened to a frog or standard.

The invention will hereinafter be first fully described with reference to the accompanying drawings, which form a part 25 of this specification, and then more particularly pointed out in the appended claims.

In said drawings: Figure 1 is a side elevation of a plow embodying my invention as seen from the moldboard side. Fig. 2 is a side elevation looking at the landside side. 30 Figs. 3 and 4 show reverse and obverse sides of the plowpoint. Figs. 5 and 6 are similar views of the frog or standard constituting a frog to which the working parts are fastened. Figs. 7 and 8 are obverse and reverse 35 views of the landside. Fig. 9 is a detail. Fig. 10 is a plan view of the landside looking down upon its upper edge.

As will be observed from the drawings, the implement in which I have incorporated 40 my improvements for the purpose of illustration herein is modeled after the general design and construction of the plow shown in my former patents No. 644,099 of February 27, 1900 and No. 740,373 of September 29, 1903, somewhat modified, though it 45 should be understood that I do not confine myself to any particular construction but reserve the right to any and all embodiments of which my said improvements are 50 susceptible.

The parts of the plow are designated in the drawings as follows:

1 is the beam; 2 is the frog or standard attached to the beam and having the working parts fastened thereon; 3 is the point; 55 4 is the moldboard; 5 is the landside.

The frog 2 is of the general form of the plow, having an oblique, sloping and concaved side 6 which provides the seat or foundation for the plowpoint and forward 60 portion of the moldboard, and having a flat landside side forming the front solid part 7 of the landside which terminates at an approximate point, and provided with a recess 8 in which fits the detachable landside 65 proper 5. The sides 6 and 7 of the frog merge into a sloping line at the front, making a comparatively heavy solid casting at the front and toe of the frog, and the sloping side 6 is joined to the recessed base portion of the landside side by a web 9, making a very firm, solid and strong foundation. The landside face is cut preferably at about 70 four inches from the point to provide the recess 8 for the landside.

For convenience, the bolts and bolt holes for fastening the working parts to the frog are indicated as follows: 10 is applied to the bolt and holes for the point; 11 and 12 indicate the two bolts and holes for the 80 moldboard; 13 and 14 the two bolts and holes for the landside. The other holes appearing in the moldboard and landside are of course for attachment of the plow-handles. The beam 1 is or may be bolted to the 85 frog at 15 and at 13 by the same bolt which secures the landside, and also by a blind bolt at 16 to hold the foot of the beam when the landside is removed for any cause. By the 90 features of my invention now to be described, the parts are effectively secured or interlocked together so that the point and landside, even if their fastening bolts should work loose, will be held firmly in place upon the frog, maintaining the original shape and 95 curvature of the plow and particularly its "suck" or "dip" as well as the inward curvature of the landside face which gives the "gather" that is necessary to make a plow run well during its life. The frog 2 100 provides a solid foundation for the plowpoint 3, which is preferably of the form substantially as shown, having an upwardly extending cutting blade or colter 17 and a lat-

eral rearwardly extending wing 18 to fit upon the sloping side of the frog below the lower edge of the moldboard. On the under or reverse side of the plowpoint, behind the 5 front cutting edge of its colter and extending to practically the point proper or toe of the plowpoint, is an elongated notch 19 in which fits the front edge and toe of the frog, it being observed that substantially the whole 10 plowpoint is thus seated upon its foundation, reducing strains tending to tilt over the plowpoint at the top; and the upper end of the colter or part 17 is provided with a beveled lug 20 which fits under the upper 15 front corner of the moldboard in a recess or under a corresponding bevel 21 therefor in the edge of the moldboard, obviating any tendency toward outward displacement at that place and holding the upper part of the 20 plowpoint firmly to its seat; while another lug 22 at the upper edge of the wing 18 engages under the lower edge of the sloping side 6 of the frog at the point 23, preventing outward displacement; and thus the plow- 25 point as a whole is always maintained fast in its proper position with its surfaces flush with the moldboard, keeping the original curvature and preventing the plow from losing its desired "suck" or "dip".

30 On the landside is incorporated a feature that is the subject matter of my United States Letters Patent No. 925,134, granted June 15, 1909; that is a beveled recess 24 on the front end of the landside 5 which receives 35 and fits under a correspondingly shaped lug 25 on the front wall of the recess 8; the purpose of which, as more fully explained in my aforesaid application, is to hold the front end of the landside 5 from outward lateral dis- 40 placement and thereby maintain the inward curvature or "gather" of the landside face of the plow necessary to hold the implement to a straight line while at work and prevent it zigzagging in the furrow and running out 45 of the land; and in conjunction with this interlocking connection at the front end of the landside there is another lug or rather a curved finger 26 at about the middle of the landside and on its inner or reverse face, 50 which lug or finger 26 hooks or locks over the rear edge of the side 7 or web 9 of the frog at the point 27 and firmly attaches the landside at that point, as well as in front, making a very rigid landside from the fact 55 that outward strain is overcome by said lug 26. The front end of the landside 5 and front wall of the recess 8 are preferably straight, which is of course the simplest way of making them, but are preferably for- 60 wardly inclined which arrangement assists in giving rigidity to the landside and in conjunction with the interlocking connections at 25 and 27 practically relieves the bolts from shearing.

It will be observed that I thus provide a 65 very practical and efficient implement, hav- ing its parts so effectively secured together as to prevent outward displacement in event of loosening of the fastening bolts and there- by preserving the original shape of the plow 70 and the correct curvature of its surfaces.

Having thus described my invention, what I claim as new and desire to secure by Letters Patent is:

1. In a plow, the combination of the plow- 75 point provided with a colter or cutting por- tion extending upwardly along the front edge of the moldboard, said colter portion having a lug on its upper part, and the moldboard under the edge of which said lug 80 is fitted and secured, to prevent the point from straining outward at the top.

2. In a plow, the combination with the frog and moldboard and plowpoint fastened thereupon, of lugs on the plowpoint one of 85 5 which engages under the edge of the mold- board and another of which engages under the edge of the frog.

3. The combination with the frog and a 90 detachable moldboard, of the detachable plowpoint formed with a colter or upwardly- 95 extending cutting portion which is provided on its rear edge with a lug engaging under the adjacent edge of the moldboard and be- 100 tween the moldboard and frog, substantially as and for the purpose described.

4. In a plow, the combination with the frog having a recess for a detachable landside, of the landside fitted therein, an interlocking connection between the front end 100 of the landside and front wall of said re- cess to prevent lateral displacement of the front end of the landside outwardly, and a lug on the rear side of the landside engag- 105 ing with the frog to hold the rear portion of the landside against lateral displacement.

5. In a plow, the combination with the frog having a recess for a detachable landside, of the landside fitted therein and bolted to the frog, and interlocking connections be- 110 tween the front end of the landside and front wall of said recess and between the rear of the landside and the frog, for the purposes set forth.

6. A plow, consisting of a frog of the gen- 115 eral form of the implement, having a flat landside face terminating in an approxi- mate point and having an oblique sloping side, a moldboard and point fitted upon and detachably fastened to said sloping side, the 120 point formed with an upwardly-extending cutting part and with a lateral wing, the frog providing a solid foundation for nearly the whole under side of the point which is seated upon the frog adjacent to the front and lower edges of the moldboard, and the flat side of the frog having a recess for a landside which extends near the front edge 125

of the frog, and a landside fitted on said recess and detachably bolted to the frog.

7. In a plow, the combination with a frog, of a plowpoint formed with a cutting edge and with a wing extending on the mold-board side of the plow, the plowpoint having an elongated notched portion that receives and abuts the front edge of the frog,

and means for fastening the plowpoint to the frog.

10

In testimony whereof I affix my signature, in presence of two witnesses.

JAMES RAPHAEL ROSSETTER.
